**ALUMINUM MOLDING FOR DOOR AND
WINDOW FRAMES**
Donald A. South, 4142 Woodmere Drive,
Youngstown 9, Ohio
Filed Dec. 7, 1962, Ser. No. 242,979
3 Claims. (Cl. 189—85)

This invention relates to a so-called built-out molding as applied to door and window frames on dwelling houses where aluminum siding and the like are being applied.

The principal object of the invention is the provision of a simple, efficient and attractive aluminum molding for application to door and window frames to build out the same relative to the adjacent wall surface.

A further object of the invention is the provision of an aluminum molding which may be easily applied to a door or window frame and which hides the fasteners used in applying the same.

A still further object of the invention is the provision of an aluminum molding which may be applied to a door or window frame without mitering or other careful fitting and in its finished arrangement has the appearance of having mitered corners and closely fitted joints.

A still further object of the invention is the provision of a built-out aluminum molding which may be rapidly installed and securely attached to a door or window frame so as to completely cover and enclose the same.

Those skilled in the art will recognize that there is a widespread practice of applying aluminum siding as well as siding of other materials to frame dwelling houses and wherein such siding is applied over the original siding, either lap or vertical batten type as the case may be, and frequently such siding is applied in connection with additional insulation so that a relatively thick layer is added to the wall and forms a new and attractive and weather-proof exterior surface. Heretofore in completing such siding jobs, it has been customary to apply a wooden "brick mold" to the existing wooden door and window frames and at the outer edges thereof where the "brick mold" which is a narrow wooden molding abuts the newly applied siding. The resulting appearance is not particularly desirable as the door frames and window frames appear to be recessed with respect to the surface plane of the new siding and the esthetic appearance of the job is therefore not right. The present invention approaches this problem and provides a means of conveniently and inexpensively building out these door and window frames so that the finished job properly locates the surface of the siding and the door and window frames in the usual and accepted manner and therefore contributes to the overall finished and proper appearance of the siding job.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

The invention is illustrated in the accompanying drawing, wherein:

FIGURE 1 is a front elevation of a built-up frame formed by the design of the invention.

FIGURE 2 is an enlarged detail elevation of the upper portion of the built-up frame seen in FIGURE 1 with parts broken away.

FIGURE 3 is an enlarged cross section on line 3—3 of FIGURE 1.

FIGURE 4 is an enlarged detail of one of the corners as seen in FIGURE 2 of the drawings.

2

FIGURE 5 is an enlarged front plane view of a portion of the horizontal built-up frame member found in the top left portion of FIGURES 1 and 2.

By referring to the drawings and FIGURES 1 and 2 in particular, it will be seen that a door sill or window sill 10 is shown with two spaced vertically standing built-up frame members 11 and 12 positioned thereon and extending upwardly therefrom and both of which built-up frame members 11 and 12 have upper end sections 13 and 14 respectively which are cut transversely thereof at right angles to the longitudinal plane thereof.

Both of the built-up frame members 11 and 12 have lower ends 15 and 16 respectively formed transversely thereof and at right angles to the longitudinal plane thereof with depending flanges 17 and 18 extending downwardly to the lowermost portion of the sill 10. Each of the built-up frame members 11 and 12 is secured to base plates 19 and 20 respectively. Each of said base plates 19 and 20 has inturned longitudinally extending edge flanges 21, 21 and 22, 22 as best seen in FIGURE 4 of the drawings. The top of the built-up frame is formed by a horizontal section of base plate 23 comprising a body portion and longitudinally extending edge flanges 24 and 25 respectively, as seen in FIGURES 2 and 4 of the drawings. The base plates 19, 20 and 23 are apertured at intervals and attached to the frame to be built-up by fasteners 26 such as screws. The abutting ends of the base plates 19, 20 and 23 are mitered in a modified manner to provide lateral edges with matching angles so that the adjacent base plate is disposed at right angles as may be seen by referring to FIGURE 4 of the drawings. It will be noted as clearly illustrated in FIGURE 4 that the miter starts inwardly of the longitudinal edge flange 24 of the base plate 23 so as to leave the flange 24 the full length of the base plate with a square corner whereas the comparable flange 22 on the base plate 20 is cut diagonally. The end of flange 25 at its juncture with the body portion of base plate 23 terminates short of the end of flange 24 and the base plate by an amount equal to the width of base plate 20 as clearly illustrated in FIG. 4. As will be pointed out again hereinafter, the plates 20 and 23 are formed from one rolled section of aluminum and thus have identical cross sections. Plates 20 and 23 accordingly are of the same width as are the flanges 22 and 24. The same configuration is formed on the opposite end of the base plate 23 where it joins the upper end of the base plate 19. It will thus be seen that the first portion of the built-up frame is formed by the three sections of the base plates 19, 20 and 23 respectively and that they provide an inverted U-shaped mounting means with substantially continuous inturned edge flanges.

The built-up frame members 11 and 12 as heretofore referred to and seen in FIGURE 1 of the drawings are rolled shapes of sheet metal as best seen in the cross section of FIGURE 3 wherein a section of the built-up frame member 12 and base plate 20 is shown. The front surface (which is the top surface in FIGURE 3) is preferably shaped in the manner of a wood molding with offset planes or face sections 12A and 12B being connected by a diagonal plane 12C and having side sections or portions 12D and 12E respectively, the ends of which are outwardly flanged as at 12F and 12G respectively. It will be seen that the flanges 12F and 12G are formed at right angles to the side sections 12D and 12E and that they are therefore capable of being slidably engaged on the base plate 20 so that they are normally positioned under the longitudinal edge flanges 22, 22 thereof with the side sections engaged by the end of the flanges 22, all as seen in the cross section in FIGURE 3 and in plan view in FIGURE 2.

By referring now to FIGURE 2 of the drawings and the lefthand portion thereof, it will be seen that a hori-

zontally disposed built-up frame member 27 of the exact same cross sectional configuration as the frame members 11 and 12 has its end portions terminating on diagonal lines or miter cuts extending from the actual ends thereof and that this built-up frame member 27 which comprises the top or horizontal portion of the built-up frame overlies the uppermost portions of the built-up frame members 11 and 12 and appears to comprise a mitered section of molding positioned between two right angularly disposed mitered sections of molding as seen in FIGURE 1. This mitered appearance between the right angularly disposed sections of identical cross section is achieved because the ends of member 27 have been cut on a 45 degree angle. The device of the invention thus provides a satisfactory appearing built-up frame complete with mitered corners. The top built-up frame member 27 is positioned by engaging its uppermost longitudinal edge flanges 29 beneath the inturned flange 24 of the base plate 23, pivoting it on this flange and swinging it downwardly in an arc and conforming thereto and bending it by moving its upper and lower sections toward one another until its lowermost edge flange 30 will be in a position to engage the inturned flange 25 on the lower edge of the base plate 23 so that upon being released it will re-assume its normal shape with its edge flanges 29 and 30 secured to the base 23 in underlying relation to the inturned flanges 24 and 25 respectively.

By referring now to FIGURE 5 of the drawings, it will be seen that each end of the built-up frame member 27 has a downturned flange 28 which overlies the upper outer sides of the built-up frame members 11 and 12 respectively. The distance between the downturned flanges 28 of member 27 can be clearly seen to be equal to the length of the flange 24 minus twice the width of flange 22. Inasmuch as the plates 20 and 23 are formed from one rolled section of aluminum as previously pointed out, it can be seen that the distance between the downturned flanges 28 of member 27 are substantially equal to the length of flange 24 of plate 23 minus twice the width of the said flange 24. The flange 29 of member 27 adjacent the downward flanges 28 has its outermost portion of a slightly less dimension than the dimension between the downturned flanges 28 as can be clearly seen from an investigation of FIGS. 5 and 1. The flanges 29 and 30 which engage the inturned flanges 24 and 25 are also clearly illustrated in FIGURE 5. It will be seen that the complete built-up frame comprises six pieces of material, three of which are formed of one rolled section of aluminum and the other three of which are formed of another rolled section of aluminum. The first three sections comprise the base plates 19, 20 and 23 with their inturned longitudinally extending edge flanges 21, 21, 22, 22 and 24, 25 respectively and the second three sections comprise the built-up frame members 11, 12 and 27 with their longitudinally extending outturned edge flanges.

It will occur to those skilled in the art that the surface contour of the built-up frame members 11, 12 and 27 may comprise any desired configuration. In assembling the frame illustrated, the three sections of base plates 19, 20 and 23 are cut at their abutting ends as heretofore described and as seen in FIGURES 1, 2 and 4 of the drawings and applied to the face of the door or window frame to be built up and secured thereto by the fasteners 26. The two-built-up frame members 11 and 12 are then cut as described with square upper and lower ends except for the depending end sections 17 and 18 and they are then placed in position by deforming them from their normal shape as seen in FIGURE 3 until the flanges 12F and 12G as seen in FIGURE 3 will be positioned so that they may be moved into normal position beneath the inturned flanges 22, 22. Next, the upper built-up frame member 27 is cut at its opposite ends to form oppositely disposed diagonal end portions and its uppermost flange 29 is positioned partially in under the in-

turned flange 24 of the base plate 23. It is then moved in an arc pivoting on that engagement of the flanges until its flange 30 is in position so that distortion of the member 27 permits both the flanges 29 and 30 to move into position beneath the inturned flanges 24 and 25 of the base plate 23. Additional fasteners (not shown) may then be positioned through the slidably engaged flanges to secure the assembly. The siding applied to the wall adjacent thereto will cover the outermost flanges 21, 24 and 22 respectively.

It will thus be seen that a simple and efficient built-up frame has been disclosed which meets the several objects of the invention, and having thus described my invention, what I claim is:

1. A sheet metal molding assembly comprising a longitudinally extending base plate having a body portion and first and second inturned flanges along the longitudinal edges thereof, said first flange extending from one end of the base plate to the other, the ends of said second flange at their juncture with the body portion terminating short of the end of the base plate by an amount equal to the width of the base plate, and a longitudinally extending hollow molding member having two outwardly extending flange portions along the longitudinal edges thereof normally positioned beneath said inturned flanges, one of the flange portions having a length less than the length of said first flange minus twice the width thereof, a side section of the member adjacent the one of the flange portions being of the same length as the said first flange minus twice the width thereof, said side section having a downturned flange at each end thereof, said member having at least one face section, the lateral edges of which are inclined inwardly of the ends of the first flange at 45 degrees when the base and member are normally positioned with said flange portions beneath said inturned flanges.

2. A built-up metal door frame molding or the like consisting of three straight sections of flat strip material having longitudinally extending inturned parallel flanges on their opposite edges arranged in an inverted U-shape with one section connecting the other two, the abutting ends of said sections having lateral edges of matching angles to form right angle turns and three sections of strip material of molding configuration having spaced parallel side portions and having longitudinally extending outturned right angular flanges along the opposite edges of said side portions, one of said sections of strip material of molding configuration being normally positioned in the section of flat strip material connecting the other two sections of flat strip material, said one of said sections of strip material of molding configuration having ends formed on a 45 degree angle to the parallel sides thereof and positioned in said built-up metal door frame in overlying relation with respect to the ends of the other two sections of strip material of molding configuration, the outturned right angular flanges of each of said sections of strip material of molding configuration being engaged beneath said inturned parallel flanges of said sections of flat strip material.

3. The built-up door frame molding of claim 2 wherein the ends of the section of flat material connecting the two sections of flat material have their matching angle lateral edges starting inwardly of one of said inturned flanges so that said one of said inturned flanges will have square end corners.
